UNITED STATES PATENT OFFICE.

RAY E. WINCHESTER, OF VINITA, OKLAHOMA.

FLUSHING-VALVE.

1,171,160.

Specification of Letters Patent.

Patented Feb. 8, 1916.

Application filed March 22, 1915. Serial No. 16,211.

To all whom it may concern:

Be it known that I, RAY E. WINCHESTER, a citizen of the United States, residing at Vinita, in the county of Craig and State of Oklahoma, have invented certain new and useful Improvements in Flushing-Valves, of which the following is a specification.

My invention relates to what are known as seat-actuated closed-tank closets, being closets in which the depression of the seat opens a valve which admits the water supply to a closed tank, which fills with water while the seat is down, and then discharges into the closet bowl when the pressure on the seat is removed.

The invention has for its object an improved construction and arrangement of the valves which control the admission and discharge of the water.

20 In such closets, as heretofore constructed, it has not been possible for the manufacturer to assemble all the parts, because of the necessity for accurately positioning them to properly coöperate with each other in 25 each individual installation. Moreover, when so installed, the seats and parts carried thereby are not interchangeable, among different closets. Also, it has been found in practice that, after the valves and seat 30 have been originally assembled and installed, they are thrown out of adjustment by slight wear of the movable parts, so that the valves do not properly close when the seat is depressed into engagement with the 35 top of the bowl. To remedy these defects, I propose to provide means by which the valves can be adjusted relative to the seat actuated device, so that such operating device may be secured to the seat by the manufacturer, and the valves adjusted accordingly when installed. By this arrangement, 40 all seats are made interchangeable, and any wear which occurs may be readily compensated.

45 In order that my invention may be clearly understood, reference is had to the accompanying drawing, forming part of this specification, and in which,

Figure 1 is a central longitudinal section 50 through my improved valve, and associated parts; and, Fig. 2 is an end elevation of the valve stem against which the operating device bears.

Referring to the drawing in detail, 1 designates a closet bowl, which may be of any 55 suitable type, and 2 indicates the seat. This

is hinged at 3 to a suitable bracket in the usual manner.

To the lower side of the seat is secured an operating device or arm 4, adapted to engage and actuate the valve stem, as herein-after described. Secured in the bowl by means of a lock nut 6 is a fitting 5, having openings 5^a through which the flushing water is discharged. To the outer end of 65 this fitting 5 is secured one end of another fitting or valve casing 7, the parts being connected by a union 9, and having an interposed gasket 8, to insure a tight joint.

The fitting 7 has formed thereon an inlet 70 connection 10, communicating with the water supply system, and a connection 11, communicating with the pressure tank (not shown). The fitting 7 is also provided with two spaced valve seats, 12 and 13, facing in 75 opposite directions, and spaced as shown.

Valves 14 and 15, preferably formed of leather or rubber, coöperate with the seats 12 and 13, respectively. The valve 14 is carried by a valve stem section 16, and the 80 valve 15 is carried by a section 18, the sections 16 and 18 being loosely coupled by means of a pin 16^a, carried by section 16, entering a socket formed in the end of section 18. The valve 15 is held in position by 85 means of a nut 17^a, which screws on to a neck 17, carried by the section 18.

The section 18 of the valve stem is in the form of a hollow sleeve, internally screw-threaded as indicated at 19. Another section 90 21, in the form of a rod, is provided with external threads 20 adapted to enter the threaded sleeve, and capable of being adjusted therein to any desired extent. A lock nut 22 is also mounted on the threaded 95 end 20 of the bar 21, and, when jammed against the end of the sleeve 18, as shown, serves to hold the parts in their adjusted position. The other end of the rod 21 is screw-threaded to receive a cap 23, preferably 100 hexagonal in shape, which carries a roller 24 adapted to be engaged by the arm or bracket 4, carried by the seat. The cap 23 works through a plug 25, set into the end of the fitting 5, and a packing ring 26, of 105 leather or the like, preferably surrounds the stem 21 to prevent leakage. Nuts 27 are positioned on a threaded portion 28 of the stem 21 to act as a stop to limit the movement of the cap 23, and prevent it from 110 becoming disengaged from the guide opening in the plug 25, as will be obvious.

Figure 1 is a central longitudinal section 50 through my improved valve, and associated parts; and, Fig. 2 is an end elevation of the valve stem against which the operating device bears.

Referring to the drawing in detail, 1 designates a closet bowl, which may be of any 55 suitable type, and 2 indicates the seat. This

A spring 29 bears at one end against a suitable cap 30, and at the other against the valve 14, and tends to hold the parts in the position shown in the drawings.

In operation, when the seat is depressed, the arm 4, acting against the roller 24, shifts the whole valve stem to the left, thus opening valve 14 and closing valve 15, permitting water to flow in through connection 10, and 10 fill the tank. When pressure is removed from the tank, the valve stem is moved to the position shown in the drawing, under the influence of the spring 29. This permits the water in the tank to be forced out and 15 thus flush the bowl through the openings 5^a.

From the above it will be seen that the arm 4 can be secured on the seat in approximately the correct position by the manufacturer. Then, when installing the fixture, the 20 plumber can adjust the rod 21 in the sleeve 18 until just the proper length of valve stem has been obtained to cause the valve 15 to close tightly when the seat 2 has been depressed into engagement with the bowl. In 25 the same way, if the parts become loose from wear, the sleeve and rod may be readily readjusted so as to take up or compensate for such wear, and thus insure the valves always closing properly. By virtue of this construction, also, any seat may be transferred 20 at will from one closet to another, the valve- stem, in each case, being adjusted to corre-

spond with the location of the arm 4 on that particular seat.

What I claim is:

The combination with a closet having a seat, of an arm carried by said seat and projecting downwardly therefrom, a casing having inlet and outlet openings, a pair of opposing valve seats formed in said casing, 40 a pair of valves coöperating with said seats to control the flow of water through said openings, and a valve stem carrying said valves, said valve stem comprising two sections, screw-threaded together within said 45 casing, said valve stem lying wholly within said casing with the exception of one end thereof, which end projects a relatively short distance beyond said casing and lies directly in the path of said downwardly extending 50 arm, whereby movement of said arm in one direction forces one of said valves toward its seat, and the other away from its seat, the above described arrangement being such that the length of said valve stem and the 55 relation between said valves and arm may be adjusted inside of said casing as required to cause the proper seating of said valves.

In testimony whereof I have affixed my signature in presence of two witnesses.

RAY E. WINCHESTER.
